DISPERSION MILLS

Ernesto Hanhausen, Mexico City, Mexico

Application October 25, 1954, Serial No. 464,475

2 Claims. (Cl. 259—43)

My invention consists in a new and useful improvement in dispersion mills and is designed to provide a capacity reduction tank removably mounted in the tank of a conventional dispersion mill. The conventional dispersion mill operates in the well-known manner as follows: the material to be dispersed is placed in the mill tank and the action of a rotor against a stator does the dispersing. The dispersed material is dumped from the tank through a discharge valve. This type of equipment was introduced to the market some years ago and has shown an outstanding performance in the paint and chemical industries. The major drawback of this type of mill is the limitation of load capacity. For example in one model of this mill the maximum capacity is approximately four hundred kilograms of material and the minimum is about two hundred and fifty kilograms. It is uneconomical for a plant to make test batches with such a mill since there is the risk of losing at least two hundred and fifty kilograms of material.

Applicant's capacity reduction tank offers a solution for this problem by permitting the mill to disperse batches of material of as low as thirty-five kilograms, thus materially widening the usefulness of the mill.

The essential novelty of applicant's device resides in the provision of a tank of considerably less capacity than that of the dispersion mill tank, and which can be so mounted in the main tank that the dispersing mechanism of the mill will operate upon material in the smaller tank, and which is provided with a novel form of discharge valve whereby the treated material can be evacuated from the device.

While I have illustrated in the drawings and herein-after fully describe one specific embodiment of my invention, it is to be distinctly understood that I do not consider my invention to be limited to said specific embodiment, but refer for its scope to the claims appended hereto.

In the drawings:

Fig. 1 is an elevation of the main tank, a portion thereof being broken away to show the capacity reduction tank mounted therein.

Fig. 2 is an enlarged top plan of the reduction tank, a portion of its upper part being broken away to show its bottom.

Fig. 3 is a vertical section on the line 3—3 of Fig. 2, in the direction of the arrows.

Fig. 4 is a side elevation exploded view of the discharge valve shown in section in Fig. 3.

As shown in the drawings, the main tank T has a bottom 1 with a central circular opening 1-a which is closed by a removable plate 2 fastened to the bottom 1 by bolts 3, a sealing gasket (not shown) is put between the bottom 1 and the plate 2 to seal the joint. Suitably mounted on the plate 2, to be positioned in the tank 1, there is a stator 5 and rotor 6 with drive pulley 6-a for dispersing material in the well-known manner. The tank T has a discharge pipe 7 in its bottom 1, on which is

2

threaded a collar 7-a exteriorly of the tank T, the purpose of which will be presently explained. The tank T may have a suitable removably mounted cover (not shown).

5 I will now describe the structure of my improved reduction tank R for use in the tank T.

The tank R has an outer jacket 8 and an inner cylindrical wall 9 to provide a cooling chamber C for circulation of water about the tank R. Water is admitted 10 through a flexible pipe 10 and discharged through a flexible pipe 11, entering the tank R at its top. The pipe 10 has a portion 10-a extending from the top to the bottom of the tank R so that the incoming cooling water is supplied to the lower end of the chamber C adjacent 15 the stator 5 and rotor 6, and rising in the chamber C is discharged through the pipe 11 at the top of the chamber C.

A suitable cover 12 is provided for the tank R and handles 13 for manipulation of the tank R.

20 The tank R has a bottom 14 with a central circular opening 14-a corresponding in diameter with the opening 1-a in the bottom 1 of the main tank T. There is provided for tank R a discharge pipe 15 passing through the bottom 14.

25 As clearly shown in Fig. 3, the tank R is mounted in the tank T by registering the openings 1-a and 14-a, the tank R passing downwardly into the tank T, about stator 5 and rotor 6, and discharge pipe 15 being received in discharge pipe 7. The bolts 3, having been removed to 30 permit placing the tank R, are then passed through registering bolts holes in the bottom 14 of the tank R and the bottom 1 of the tank T. When these bolts 3 are secured, the tank R is in operative position.

35 The discharge pipe 15 has on its upper end flush with the top surface of the bottom 14 of the tank R a valve seat 15-a.

It is to be understood that the main tank T has a suitable valve (not shown) for controlling the discharge of material from the tank T through the pipe 7.

40 When this valve has been removed, a valve member 16 with a stem 16-a is inserted into tank R, the member 16 seating on seat 15-a and the stem 16-a extending downwardly through pipes 15 and 7.

45 A discharge pipe 17 is then coupled to collar 7-a by bolts 7-b. This pipe 17 has an angular part 18 which can be attached to any suitable conduit (not shown) to carry off the discharged material. A bore 18-a is provided in part 18 coaxial with pipes 7 and 15, through 50 which stem 16-a passes. The pipe 17 has a depending sleeve 19 co-axial with the stem 16-a and having a closure plate 19-a in its lower end. Suitably threaded in the plate 19-a is an adjusting nut 20 having a knurled handle 20-a outside of sleeve 19 and a central bore 20-b. The part 18 has an abutment 18-b about the bore 18-a and within the sleeve 19. An expansion spring 21 bearing on the top of nut 20 biases a washer 21-a against the abutment 18-b to seal the bore 18-a. A cotter pin 22 passes through a bore 20-c in the nut 20 and a bore 16-b in the stem 16-a, to fix the nut 20 on the stem 16-a.

55 From the foregoing description of the details of construction of my improved capacity reduction tank, its use and operation is obvious. Manipulation of the handle 20-a of the nut 20 adjusts the valve member 16 relative to the valve seat 15-a, to open and close the discharge pipe 15.

60 When the tank R has been seated in the tank T, as above described, and the pipe 15 has been closed by seating valve member 16 on the valve seat 15-a, the top 70 12 is moved to open position (Fig. 3), and the tank R is charged with the material to be dispersed by action of

stator 5 and rotor 6, now within the tank R. The top 12 is closed and the mill is operated in the usual manner. The dispersed material can be evacuated from the tank R through the pipe 15 within the pipe 7 of tank T, and discharged through the pipe 17 and its part 18, by opening pipe 15 by moving the valve element 16 off of the seat 15-a.

Having described my invention, what I claim is:

1. In a capacity reduction tank, for a dispersion mill having a main tank with a discharge pipe and a circular opening in its bottom and a circular plate to cover said opening, said plate carrying dispersion mechanism comprising a stator fixed on the plate and in the main tank and a rotor in said stator, said plate and the bottom of the main tank having sets of registering bolt holes, respectively, the combination of a reduction tank so dimensioned as to have a lesser capacity than the main tank and to be disposed in the main tank, said reduction tank having a circular opening in its bottom of the same diameter as the opening in the bottom of the main tank and having a series of bolt holes registering with those

in the plate and the bottom of the main tank, and a set of bolts received in said bolt holes, whereby the parts can be alternatively related to dispose the dispersion mechanism in the main tank when the reduction tank is not disposed in the main tank, and to dispose said mechanism in the reduction tank when the reduction tank is disposed in the main tank, respectively.

2. The structure defined by claim 1, having a discharge pipe on the reduction tank passing through said discharge pipe in the main tank, with a valve seat in said reduction tank, a valve member co-acting with said seat to open and close the reduction tank discharge pipe, and a stem on said member passing through said discharge pipe of the reduction tank and extending outside of the main tank when the reduction tank is in the main tank.
